UNITED STATES PATENT OFFICE.

DAVID A. E. JOHNSTON, OF HELENA, ARKANSAS.

TYPE-WRITER ATTACHMENT.

1,214,169.

Specification of Letters Patent. Patented Jan. 30, 1917.

Application filed January 23, 1913. Serial No. 743,773.

To all whom it may concern:

Be it known that I, DAVID A. E. JOHNSTON, a citizen of the United States, residing at Helena, in the county of Phillips and 5 State of Arkansas, have invented certain new and useful Improvements in Type-Writer Attachments, of which the following is a specification.

My invention relates to an improvement 10 in typewriter attachments, and more particularly to means for storing and holding a continuous supply of paper for the machine, so that the same will always be in condition for use by the operator, and therefore 15 by avoid the interruption commonly occasioned by the removal of a written sheet and the insertion of a new one.

A further object is to make a device that 20 will be attachable to an ordinary machine, and which may be separately manufactured and kept in stock by a supply house.

In the drawings forming a part of this 25 specification, and in which like symbols of reference represent corresponding parts in the several views: Figure 1 is a plan view of the device attached to a typewriter; Fig. 2 is a transverse sectional view, on the line 2—2, of Fig. 1; Fig. 3 a longitudinal section of the device for storing and feeding 30 the paper; Fig. 4 a view of a slotted lug for attaching it to a typewriter; and Fig. 5 a modification of the attaching means, showing a clip to clamp the frame of the typewriter.

35 1 represents the cylinder of my attachment; and 2 the shaft carrying the same, said shaft having a groove 3 formed in the same and angularly inclined, so as to hold the paper when the same is inserted in said 40 groove and rolled in an opposite direction to the inclination of the groove upon said shaft. The shaft is also provided with the usual handles 4 to operate the same; and disks 5 to hold the paper in proper relation 45 thereon, the same being held by means of collars 6 and screws passing through the same and against the shaft; or they may be rigidly fixed thereto, if desired.

7 are disks near the ends of the shaft 2 50 to hold it in its proper relation within the cylinder; 8 is the platen of the typewriter; and 9 the paper table to which the device is attached.

10 represents the paper being fed from the roll, the same passing around the platen of 55 the typewriter and back and upward under the paper-cutter 11 on cylinder 1, when it can be severed, as desired.

12 are lugs connected to the cylinder 1 for the purpose of fastening the same to 60 the paper table, or other part of the typewriter, by screws 15; and 13 is a modification, showing a clip which may be used in lieu of lugs 12, the same being adapted to clamp the device to the paper table of the 65 typewriter. Of course in typewriters where the form of attachment shown would not be applicable, other well known mechanical expedients may be employed, as desired, 70 for supporting the device on the same.

The operation of the device will be apparent from the foregoing description of the same. A number of storage cylinders may be provided for a typewriter so that when one is used up another may be placed 75 on the machine. When the device is connected to a machine, to the paper table or other suitable part, the paper is directed along said table under the platen of the typewriter and as said platen is operated it 80 is fed from said roll, the reverse or winding movement being obtained by the operator turning handle 4. When the letter is finished it passes under knife 11, where it can be easily severed, if desired.

Having now fully described my invention, what I claim as new and desire to secure by Letters Patent, is:—

An attachment for typewriters, comprising a cylinder; means depending from said 90 cylinder and formed to engage and clamp a paper table; said cylinder having a longitudinal slot near its lower side through which a web of paper may pass; a shaft supported in said cylinder, said shaft having a longitudinal slot to receive and hold the end of said web, and disks to confine the roll of paper in proper position; and a paper cutter carried by, but separated 95 from, the upper side of the cylinder.

In testimony whereof I affix my signature in presence of two witnesses.

DAVID A. E. JOHNSTON.
